F. H. COOK

BOTTLE HOLDER

Filed June 29, 1923

UNITED STATES PATENT OFFICE.

FREDERICK H. COOK, OF TIPPECANOE, OHIO.

BOTTLE HOLDER.

Application filed June 29, 1923. Serial No. 648,436.

To all whom it may concern:

Be it known that I, FREDERICK H. COOK, a citizen of the United States, residing at Tippecanoe, in the county of Miami and State of Ohio, have invented certain new and useful Improvements in Bottle Holders, of which the following is a specification.

My invention relates to a safety deposit box for milk bottles and the like, the purpose of which is to prevent the bottle being stolen or removed by unauthorized persons and as an equally important feature of the invention to compel the return of empty bottles by requiring the insertion of a second bottle in the box or receiver in order to release the full bottle.

The device is automatically adaptable to bottles of different sizes as half pints, pints and quarts. In a simplified form the invention includes a housing or box having therein two yielding or expanding receivers for bottles, which are deposited therein from the top. The box or housing is provided with a sliding cover movable to and fro to expose and afford access first to one and then to the other of such receivers. Detent means is provided for locking this reciprocatory cover at either end of its path of travel, and hence in position to cover and protect the bottle deposited in either of such receivers. Stop fingers or rests are provided at different levels for the different sizes of bottles controlled by the expansion of the receivers to accommodate the bottles of different sizes, whereby when a pint bottle is inserted, the half pint rest is withdrawn and upon insertion of a quart bottle, the stop or rest pertaining to both the half pint and pint sizes are retracted. Trip means is provided for the lid lock, controlled by the insertion of the bottle in the closed receiver, thereby permitting the cover to be retracted to afford access to the bottle in the opposite compartment or receiver, the removal of which permits the engagement of the lid in its operated position to protect the inserted bottle.

The object of the invention is to simplify the structure as well as the means and mode of operation of such safety deposit devices,

whereby they will not only be cheapened in construction, but will be more efficient in use, positive in operation, automatic in action, easily operated, and unlikely to get out of repair.

A further object of the invention is to provide an improved form of container, and lockable closure therefor.

A further object of the invention is to provide bottle protective means operated by the insertion of a second bottle, thereby necessitating the return of empty bottles by the customer, and protecting the deposited bottles against thievery and the depredations of stray animals, as well as against freezing in winter and extreme heat in summer.

A further object of the invention is to provide simple and automatic stop control means, for adapting the device to bottles of different sizes, and to further provide a simple and economical form of bottle controlled lock for the closure.

In order that safety devices of this character may be generally used, it is quite necessary that they be of nominal cost, which may be offset by the return to the distributing company of a greater number of empty bottles, sufficient to afford a profitable saving. Moreover, such device must be substantially "fool proof" and of such character as to not necessitate loss of time in locking or unlocking the depository box by the deliveryman. With these objects in view, it is the object of the present invention to afford a deposit box which will meet the commercial requirements of economy, utility and safety.

With the above primary and other incidental objects in view as will more fully appear in the specification, the invention consists of the features of construction, the parts and combinations thereof, and the mode of operation or their equivalents as hereinafter described and set forth in the claims.

Referring to the drawings, Fig. 1 is a perspective view of the deposit box forming the subject matter hereof. Fig. 2 is a side elevation with the housing in section, to disclose the interior mechanism. Fig. 3 is a

top plan view and Fig. 4 a detail transverse sectional view, on lines 3—3 and 4—4 of Figs. 2 and 3 respectively. Fig. 5 is a detail of a modification of the bottle stop or rest. Fig. 6 is a detail view of the closure lid in inverted position. Fig. 7 is a diagrammatic view of the operation of the bottle stops.

Like parts are indicated by similar characters of reference throughout the several views.

In the embodiment of the invention illustrated in the drawings, 1 is the box or housing, having in the top thereof, two spaced access openings 3—3. Slidingly mounted on top of the housing or box 1 is a reciprocatory closure lid 2, movable to and fro into registry alternately with the respective access openings 3. Located within the housing 1 in registry with the respective openings 3, are two yielding or expansible receivers for the bottles, each comprising two arcuate swinging side sections 4—4, pivotally mounted in spaced relation upon vertically disposed supporting shafts or rods 5. At their upper ends these swinging side walls 4 are outwardly flared or flanged at 6, thus affording a flaring mouth or guide for the receiver, through which the bottle is introduced. The swinging receiver walls 4 are spring pressed inwardly toward each other, so that when empty they conform substantially to the diameter of the smallest bottle to be received. This bottle is usually the half pint size. The actuating springs may be applied in any suitable manner, as for instance, helical springs surrounding the supporting shaft or rod 5, one end of which are engaged with the swinging walls 4 as shown at 7. In lieu of such spring construction, spring actuated bottle stops or rests 8 and 9 may be relied upon to also actuate the receiver walls 4. In Figs. 2 and 3 there are shown two of these bottle stops for each receiver. These stops 8 and 9 comprise swinging arms pivotally mounted upon the inner side of the side wall of the housing and projecting thence through suitably located openings in the swinging walls 4 of the receiver to the interior thereof. The bottle stops 8 and 9 are of arcuate form, and are of different lengths, each arm is provided with an actuating spring 10, tending to turn the stop arm or rest inwardly and carry with it the side wall 4 of the receiver. These stop arms or rests 8 and 9 normally project into the path of movement of the bottles within the receiver and are located at such height that the corresponding bottle when resting upon the stop arm or rest will extend into approximate relation with the access opening 3. The uppermost arm 8 pertains to the half pint bottle and extends within the receiver to support the half pint bottle in elevated position. However, upon the in-

trodition of a pint bottle within the receiver or intermediate the swinging walls 4—4, these walls are forced outwardly against their actuating spring. The swinging movement of the side walls 4 is transmitted to the stop arms 8 and 9 oscillating these arms also outwardly in unison with the movement of the walls 4, thereby withdrawing the uppermost stop arm or rest 8 from the path of the pint bottle being introduced. The lower stop arm being of somewhat different curve, will continue to protrude within the receiver or intermediate the walls 4—4, after the stop arm 8 has been oscillated therefrom. The arm 9 will, therefore, be engaged by the pint bottle being introduced and will support the bottle in an elevated position above the bottom of the housing 1 with its top in juxtaposition to the opening 3. If, however, a quart bottle is introduced through the opening 3 into the receiver, the increased diameter of such quart bottle will force the swinging walls 4—4 of the receiver outwardly a greater distance, carrying with them the stop arms or rests 8 and 9 and effecting the withdrawal of both of such arms from the interior of the receiver, allowing the quart bottle to pass downwardly until it rests upon the bottom of the housing or box 1. Thus the receiver is universal in its adaptation to bottles of different sizes, and operates to support the different bottles with their tops at substantially the same level and within easy access through the opening 3. In order to lock the sliding lid in registry with either of the access openings 3, so long as the opposite receiver remains empty, there is provided on the under side of such sliding closure lid 2, parallel rack bars or ratchet bars 11, the teeth of which are imposed in opposite relation, and each of which is engaged by a spring actuated detent plunger 12. The plungers 12 are slidingly mounted upon a supporting plate 13 vertically positioned centrally within the housing or box 1. Preferably one such detent plunger 12 is mounted upon each side of the plate 13 and in a plane common with the corresponding ratchet bar 11, carried by the closure lid. Each detent plunger 12 is connected by a stud 14, with an arcuate trip lever 15, pivoted at 16 to the supporting plate 13. The arcuate trip levers 15 are oppositely disposed and extend intermediate the swinging side walls 4—4 of the respective bottle receivers to the interior of such receivers and into the path of movement of the bottles as they are inserted between such swinging walls. So long as the bottle receiver is empty, the detent spring 17 will maintain the corresponding detent plunger 12 in engagement with its corresponding ratchet bar 11. This spring pressed detent plunger will permit the movement of the closure lid 2 in

one direction only to close the opposite receiver and access opening 2, but will prevent any return movement of the closure lid. Upon the introduction of a bottle into the receiver through the uncovered opening 3, the engagement of such bottle whether of large or small size with the arcuate trip lever 15 will oscillate such lever to withdraw the plunger 12 from engagement with the ratchet bar 11 against the tension of its spring 17, thereby releasing the closure lid for shifting movement into position over the bottle receiver just filled, and thus uncovering the bottle in the opposite receiver. Upon the removal of the bottle from the uncovered receiver, the release of the trip arm permits the detent plunger to engage the ratchet bar corresponding to such receiver to lock the lid in its adjusted position.

In lieu of the independent swinging stop arms or rests 8 and 9, both of these stops or rests may be carried on a single arm as shown in Fig. 5. In such case, the stops are of different length and of different curvature, and in such case would depend for operation upon one of the swinging side walls 4 only. The operation and function is quite the same, the initial swinging movement of the wall to accommodate a pint bottle being sufficient to withdraw the half pint bottle or rest 8' while the introduction of a quart bottle will swing the side wall 4, sufficient distance to attract the withdrawal of the pint bottle stop or rest 9'. This double stop arm is preferably spring pressed, as before described, but in the event of its use the opposite swinging wall 4 must be provided with an independent actuating spring, preferably though not necessarily as shown at 7.

In addition to the bottle operated detent before described for locking the sliding closure, this closure may be provided with a key operated snap lock 20, which serves to lock the slide closer over one of the receivers only, and is controlled solely by the customer. Such additional lock 20 would prevent an unauthorized person from removing the full bottle of milk by introducing an empty bottle in the opposite side of the deposit box. In such event it would require both the deposit of the empty bottle and the use of the key to enable the removal of the full bottle. However, such snap lock would not at all interfere with the operation of the delivery man, who finding the locked compartment open would deposit the full bottle therein, slide the cover over into its snap lock position, and remove the empty bottle from the other side.

In operation the box is secured against bodily removal by means of screws or bolts introduced preferably through the interior of the housing. The deliveryman deposits the full bottle of milk in the receiver through the openings 3, and slides the closer lid over such

deposited bottle to protect it against removal and removes the exposed empty bottle. This leaves the opposite compartment or receiver empty. The closure is held in its adjusted position by means of the detent 70 plunger 12. In order to release the closure and withdraw the detent the customer must deposit in the compartment or receiver, another bottle, which by its engagement with the arcuate trip lever 15 releases the 75 closure lid 2, which may then be drawn to its opposite position and the full bottle removed. Upon removal of the full bottle, the closure lid is locked in its position over the empty bottle and the deliveryman can 80 not take the empty bottle without leaving a full bottle in its place. The device not only insures the prompt return of empty bottles by the customer, but it also serves as a check upon the deliveryman, who upon his neglect 85 or failure to leave a bottle of milk cannot say that it had been left and stolen or that the customer misrepresented the fact that he did not receive the bottle.

While the side walls 4-4 of the bottle receiver or compartment have been shown constructed from sheet metal for economy of manufacture, it is obvious that these swinging walls or compartment sides may be of open mesh formature and the bottle receiver in the form of a cage. It is to be understood that the construction illustrated disclosed the invention in a simplified form, and is not necessarily the only form of embodiment of the invention.

From the above description it will be apparent that there is thus provided a device of the character described possessing the particular features of advantage before enumerated as desirable, but which obviously 105 is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific details 110 shown, but that the means and construction herein disclosed comprises the preferred form of several modes of putting the invention into effect and the invention is, therefore, claimed in any of its forms or 115 modifications within the legitimate and valid scope of the appended claims.

Having thus described my invention, I claim:

1. In a bottle receiver, an expandible and 125 contractible bottle receiving compartment, a bottle rest projecting within said compartment to support a bottle of reduced size, the expandible compartment and bottle rest being operatively interconnected whereby the 130

- expansion of the compartment to accommodate a bottle of larger size will automatically effect the withdrawal of the bottle rest to permit the passage of the larger bottle therebeyond.
5. In a bottle holder, a bottle receiving compartment, a bottle rest extending within the compartment for supporting a bottle of reduced size in elevated position, and yielding control means engaged by a bottle of larger size for withdrawing the bottle rest to permit the larger bottle to descend beyond said rest.
10. 2. In a bottle holder, a box having a sliding top, two bottle compartments within the box into registry with which the sliding top is alternately movable, a locking detent for said sliding top for locking said top in registry with one of said compartments, and release means for said detent operable by the insertion of a bottle in the open compartment.
15. 3. A bottle holder for bottles of different sizes, comprising an expansible and contractible bottle receiving compartment, a bottle rest therein for supporting a bottle of reduced size in elevated position, the expansion of said compartment to accommodate a bottle of larger size being adapted to effect the withdrawal of the bottle rest to permit the descent of the larger bottle to lower level.
20. 4. A bottle holder for bottles of different sizes, comprising a bottle receiving compartment, a bottle rest normally positioned therein, for supporting a bottle of reduced size in elevated position, and yielding control means therefor engaged by a bottle of larger size upon insertion within the compartment for withdrawing the bottle rest to permit the descent of the larger bottle to lower level.
25. 5. In a bottle holder, a housing having two bottle receiving compartments, an alternating closure for the compartments adapted to close either of the compartments and open the other, detent means for said closure for maintaining the closure in closed relation with one of the compartments, and means controlled by the insertion of a bottle in the open compartment for releasing the detent.
30. 6. In a bottle holder, a housing adapted to receive two bottles, a reciprocatory closure for the housing movable from the path of removal of one bottle into that of the other, and detent means for the closure whereby said closure is retained in its adjusted position so long as only one bottle is contained within the housing.
35. 7. In a bottle holder, a housing to receive a plurality of bottles, an adjustable closure for said housing rendering different portions of the housing alternately accessible and inaccessible, and adapted to prevent the removal of a bottle contained therein, detent means for said closure, and means for releasing the closure by the insertion of an additional bottle into the accessible portion of said housing.
40. 8. In a bottle holder, a container into which more than one bottle may be deposited, an alternating closure for rendering the deposited bottles within the holder alternately accessible and inaccessible, a lock for said closure preventing access to the en-
- closed bottle, and release means for the lock operated by the deposit of bottles alternately in one portion and then in another of the housing to release the closure and permit the removal of the previously deposited bottle.
45. 9. In a bottle holder, a box having a sliding top, two bottle compartments within the box into registry with which the sliding top is alternately movable, a locking detent for said sliding top for locking said top in registry with one of said compartments, and release means for said detent operable by the insertion of a bottle in the open compartment.
50. 10. In a bottle holder, a box having a sliding top, two bottle compartments within the box into registry with which the sliding top is alternately movable, independent locking detents for retaining the sliding top in registry with the respective compartments, there being one detent for each compartment, and release means for the detent pertaining to each compartment operable by the insertion of a bottle in the other compartment.
55. 11. In a receiver for bottles of different sizes, a retractile stop for a bottle of smaller size and means for automatically retracting the stop by the insertion of a bottle of larger size.
60. 12. In a bottle receiver, a compartment into which bottles of different size are to be inserted, stop rests projecting into the compartment at different levels upon which the bottles of different sizes may be supported, and means for automatically retracting the stop rests pertaining to bottles of smaller size by the insertion of a bottle of larger size.
65. 13. In a receiver for bottles of different sizes, adjustable rests upon which bottles of different height may be supported at different elevations and means controlled by the diameter of the bottle inserted for automatically adjusting the bottle rests.
70. 14. In a bottle receiver, means for supporting bottles of different sizes at different elevations and means for automatically varying the elevation at which the bottle is supported in accordance with its diameter.
75. 15. In a bottle holder, a housing of sufficient size to receive two bottles, a closure lid for the housing shiftable to alternate positions in either of which positions it may cover and prevent removal of one bottle, leaving the other bottle if in the housing exposed and free for removal, and a detent for said closure lid controlled by the insertion and removal of a bottle into and from the holder and operating to lock the closure lid upon removal of a bottle and to release the lid upon insertion of a bottle.
80. 16. In a bottle holder, a housing having separate bottle compartments therein, a

closure lid pertaining to the housing, movable to alternate positions in each of which it closes one compartment and opens another, a ratchet member movable with said closure lid, a detent pawl movable into and out of engagement with the ratchet member, means for withdrawing the detent from

engagement with the ratchet member upon insertion of a bottle, and means for reengaging the detent pawl with the ratchet member upon removal of a bottle.

In testimony whereof, I have hereunto set my hand this 6 day of June A. D. 1923.

FREDERICK H. COOK.
